UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

LIQUID-COATING MACHINE.

Application filed April 27, 1921. Serial No. 464,839.

To all whom it may concern:

Be it known that I, FREDERICK COATES, a citizen of the United States, residing at Cincinnati, in the county of Hamilton and 5 State of Ohio, have invented certain new and useful Improvements in Liquid-Coating Machines, of which the following is a specification.

This invention relates to the art of liquid 10 coating and has special reference to a manually operable machine which I term a liquid applier and which is used for water-proofing and gumming the tops of paper containers or cans.

15 One important object of the invention is to improve and simplify the general construction of devices of this character.

A second important object of the invention 20 is to provide an improved and simple machine wherein both the water-proofing or oil-proofing and the gum may be properly applied to a can top without making it necessary for the operator to hold the top or to soil his hands with the liquid to be applied.

25 A third important object of the invention is to provide an improved and simple machine arranged to enable a practically unskilled operator to apply water or oil-proofing and gum to a paper can top.

With the above and other objects in view, the invention consists in general of certain novel details of construction and combinations of parts hereinafter fully described, 35 illustrated in the accompanying drawings, and specifically claimed.

In the accompanying drawings, like characters of reference indicate like parts in the several views, and:-

40 Figure 1 is a plan view of a liquid applier constructed in accordance with this invention.

Figure 2 is a side elevation thereof.

Figure 3 is an enlarged detail section on 45 the median plane of Figure 2.

In carrying out the objects of this invention there is provided a pair of stands 10 each of which carries a tank 11, one of said tanks being for the purpose of receiving a 50 water or oil proofing composition while the other tank receives a liquid glue or gum. These tanks are connected in spaced relation by a frame 12. At each end of each tank is a suitable bearing 13. The bearings 55 all being alined and through these bearings

extends a shaft 14 having on one end a drive pulley 15 so that the shaft may be driven by a belt 16. It is, of course, obvious that other means of driving may be utilized. Within each of the tanks 11 there is fixed 60 to the shaft 14 a feed roller or drum 17. Extending diagonally outward from the frame 12 are brackets 18 and at the outer end of each bracket is a pivotally mounted fork 19 between the arms of which is tiltably 65 mounted a rod 20 carrying at its inner end a brush 21, the outer end of said rod being used for a handle.

By means of this construction the brush 21 may be brought into contact with the revolving feed roller 17 of the respective tank 70 or may be swung to any desired position away from such feed roller.

Extending forwardly from the frame 12 is a bearing boss 22 which is hollow and 75 opens toward the rear of the machine. Through this bearing boss extends a hollow shaft 23 which carries on its upper end a disk 24 provided with a centrally disposed recess in its upper face wherein feeds a strip 80 plate 25 mounted on an ejector rod 26 extending through the hollow shaft and provided on its lower end with a striking knob 27. Secured to the shaft 23 within the bearing boss is a spiral gear 28 which meshes 85 with a spiral gear 29 fixed upon the shaft 14.

In the operation of the device the operator places on the disk 24 a can top such as the top prepared by the die press illustrated and described in my copending application 90 filed the 27th day of April, 1921, and bearing the Serial Number 464,833. The revolution of the shaft 14 causes the lower peripheral portions of the feed roller 17 to constantly move upward and as these lower portions 95 dip into the contents of the respective tanks the upper portions of these feed rollers are coated with a thin film of the material to be applied. The operator places the brushes on the feed rollers by proper manipulation 100 of the rods 20. Next the brush for coating the top with water or oil-proofing is swung into position to lie on top of the paper can top or closure as shown in dotted lines in Figure 1. It is to be noted that during the 105 entire operation the shaft 23 is rotated by the action of the spiral gears. This rotation frictionally causes rotation of the can top beneath the moistened brush 21 thus applying the liquid evenly over its surface. As 110

the water or oil-proofing is accomplished this brush is swung back to engagement with its feed roller and the other brush is moved into position in the channel of the can top as also shown in dotted lines in Figure 1. This affects coating of the entire inside of the channel with the liquid adhesive. After this coating is accomplished the brush is swung back to its feed roller and the operator, by a smart tap on the striking knob 27, disengages the can top from the carrier disk 24. The can top may then be lifted off and another top put in position for further operation.

There has thus been provided a simple and efficient device of the kind described and for the purpose specified.

It is obvious that minor changes may be made in the form and construction of the invention without departing from the material principles thereof. It is not therefore desired to confine the invention to the exact form herein shown and described, but it is wished to include all such as properly come within the scope claimed.

Having thus described the invention, what is claimed as new, is:—

1. In a device of the kind described, an article support, a tank adjacent said support, a feed roller revolvably mounted in said tank and arranged to have its lower portion dip into the contents of the tank, an operating rod pivotally and tiltably mounted adjacent the tank, a fluid applying device carried by the rod and movable therewith to engage selectively with the upper part of the roller and an article on the support, and means to constantly rotate the roller and article support.

2. In a device of the kind described, an article support, a tank adjacent said support, a feed roller revolvably mounted in said tank and arranged to have its lower portion dip into the contents of the tank, an operating rod pivotally and tiltably mounted adjacent the tank, a fluid applying device carried by the rod and movable therewith to engage selectively with the upper part of the roller and an article on the support, and means to constantly rotate the roller and

article support comprising a shaft whereon said roller is mounted, driving means to the shaft, a second shaft carrying the article support, and gearing connecting said shafts.

3. In a device of the kind described, an article support, a tank adjacent said support, a feed roller revolvably mounted in said tank and arranged to have its lower portion dip into the contents of the tank, an operating rod pivotally and tiltably mounted adjacent the tank, a fluid applying device carried by the rod and movable therewith to engage selectively with the upper part of the roller and an article on the support, means to constantly rotate the roller and article support, and an article ejector associated with the article support and operable during movement thereof.

4. In a device of the kind described, an article support, a tank adjacent said support, a feed roller revolvably mounted in said tank and arranged to have its lower portion dip into the contents of the tank, an operating rod pivotally and tiltably mounted adjacent the tank, a fluid applying device carried by the rod and movable therewith to engage selectively with the upper part of the roller and an article on the support, means to constantly rotate the roller and article support comprising a shaft whereon said roller is mounted, driving means for the shaft, a second shaft carrying the article support, gearing connecting said shafts, and an article ejector associated with the article support and operable during movement thereof.

5. In a device of the kind described, a can top support including a disk whereon a can top may fit and having a recess in its upper face, a hollow shaft carrying said disk, means to rotate the shaft, an ejector plate normally resting in the recess, a plunger carrying the ejector plate and extending through the hollow shaft with its lower end projecting normally below the lower end of said shaft, and means to apply fluid to a can top held upon said support.

In testimony whereof I affix my signature.

FREDERICK COATES.
